UNITED STATES PATENT OFFICE

2,006,253

MOVABLE WEIR

Hans Zimmermann, Dortmund, Germany, assignor to the firm Vereinigte Stahlwerke Aktiengesellschaft, of Dusseldorf, Germany

Application July 9, 1934, Serial No. 734,412
In Germany October 29, 1931

3 Claims. (Cl. 61—28)

The invention relates to an improvement in movable weirs of the Stoney roller type the body of which has a quadrangular cross section, and more especially to an improved connection of the weir body to the wheel supports at the ends of the same, which connection is most advantageous for sluice weirs with large distance of supports.

According to the invention the quadrangular weir body is at its ends so constructed, that the end members of the tail water beams of the main girders are in the end field inclined from the horizontal main girder levels so that they converge in the perpendicular line passing through them in the level of the end plate and meet in a single point. Thus the said end members form a triangle in the perpendicular level of the end plates. By this means a considerable expenditure of iron structure or masonry as in the known constructions is avoided.

The invention is more clearly described by way of example in the accompanying drawing, in which

Fig. 1 is a cross-section of the novel connection between the quadrangular weir body and its end plates according to line 1—1 of Fig. 2,

Fig. 2 is a plan view according to Fig. 1,

Fig. 3 is a cross section through line 3—3 of Fig. 2, and

Fig. 4 is a side-view according to Fig. 2.

In Fig. 1 the triangular form of the weir body structure in the level of the end plate 8 is shown, while in Fig. 3 the quadrangular cross-section of the weir body is represented with the top and the bottom main girder 45 and 44 respectively and the separate head water beams 47 and 46 respectively and separate tail water beams 6_o and 6_u respectively. In order to better distinguish the single members of the beams in Figs. 2 and 4 the indices a, b and c are used for the beam members 46 and 47 and the indices 1, 2 and 3 for the members 6_o and 6_u. According to the invention the end members 6_{o1} and 6_{u1} respectively of the tail water beams of the main girders 44 and 45 are in the end field so inclined from the horizontal main girder levels that they converge in the perpendicular line passing through them in the level of the end plate (Fig. 4). They thus form a triangle with the members 33', 34' and 43 in the area of the perpendicular connection of the beams 6_o and 6_u which with its base therefore rest immediately on the end plates 8. 9 and 10 are the bearings with which the end plate 8 rests upon the bogie wagons or supporting wheels 11 and 12, and 41 is

the pier with its recess 42 in which the weir can be moved. 43 is the weir wall or skin plate of the weir body with which the main girders 44 and 45 and the head water beams 46 and 47 are connected.

In contradistinction thereto the hitherto used construction with a quadrangular weir section made it necessary either to enlarge the axle base of the supporting wheels or the breadth of the pier recess in order to properly connect the weir body with the end plate. The first mentioned arrangement requires a greater length and bending stress of the end plate 8, i. e. a considerable additional expenditure in iron structures and generally a pit in the recess base as well as a heightening of the pier which entails additional expenditure of masonry and at the same time disadvantages in operation (accumulation of mud or settling of stones in the pit of the supporting wheels). The latter arrangement necessitates a considerable increase of the recess width and therefore an enlargement of the pier which also means an additional expenditure of masonry. For these reasons constructors have hitherto desisted therefrom and have rather put up with the construction of the main girders with their disadvantageous consequences in respect of the oscillation rigidity of the weir.

What I claim and desire to secure by Letters Patent of the United States is:

1. Movable weir of the Stoney roller type the body of which has a quadrangular cross-section comprising a weir wall, upper and lower main girders, the said main girders being substantially parallel and connected at their one end with the weir wall, beams at the ends of the main girders, lateral end plates to which the beams are connected, the beams at the free ends of the main girders being substantially parallel in a horizontal level except their end members in the end field, which end members are so inclined that they converge and intersect each other in the end plates in a single point so that a triangle of beams is formed in the end fields.

2. Movable weir of the Stoney roller type the body of which has a quadrangular cross-section, comprising a weir wall, upper and lower main girders which are substantially parallel and connected at their one end with the weir wall, upper and lower head water beams and tail water beams at the ends of the main girders, lateral end plates to which the beams are connected, the head water beams being arranged parallel to one another at the weir wall, the tail water beams being substantially parallel to the weir wall from

end plate to end plate and parallel to one another in a horizontal level except their end members in the end field, which end members are so inclined that they converge and intersect each other in the end plates in a single point so that a triangle of beams is formed in the end fields.

3. Movable weir of the Stoney roller type the body of which has a quadrangular cross-section, comprising a weir wall, upper and lower main girders which are substantially parallel and connected at their one end with the weir wall, upper and lower head water beams and tail water beams at the ends of the main girders, lateral end plates to which the beams are connected, the head water beams being arranged parallel to one

another at the weir wall, the tail water beams being substantially parallel to the weir wall from end plate to end plate and parallel to one another in a horizontal level except their end members in the end field, which end members are so inclined that they converge and intersect each other in the end plates in a single point so that a triangle of beams is formed in the end plates, bearings at the tail water side of the end plates, bogie wagons for supporting and moving the weir body, the said bogie wagons being connected with the bearings of the end plates and arranged close below and above the intersecting point of the tail water beams. 5

HANS ZIMMERMANN. 15
